METHOD OF LAYING ROOFING SHEETS

Arthur Winding, Milwaukee, Wis.

Application June 5, 1933, Serial No. 674,356

6 Claims. (Cl. 108—7)

This invention relates to a novel method of laying prepared composite sheet roofing and to the roofing when laid.

Prepared roofing of the character referred to, is furnished by the manufacturer in relatively long, sheet-like strips, in rolled form. The necessary ingredients of the material are secured together in a homogeneous mass by a bituminous binder which is incorporated in the material at 5 the time of its manufacture. This binder is of course set when the material is placed on the market and gives the material the rigidity and hardness required for a roof covering. While this binder renders the material relatively stiff 10 and rigid, the material is not so inflexible that it cannot be supplied in rolled form or be readily and easily unrolled for roof applying purposes. In laying the material, the practice heretofore has been to mop or coat the underlying support 15 with a hot flowable pitch or asphalt to the width and length of the roofing strip to be laid and then unroll the strip on the coated support. This method of laying produces an imperfect and ineffective bond between the strip and the support 20 because portions of the coating not infrequently cool off and set before reached by the strip and because the strip by reason of the set binder therein is far too inflexible to be properly pressed against the coated support and conform 25 to the contour thereof. This contour in most cases is quite irregular and replete with high points and depressions over its entire surface. Thus a roof covering secured in this way will readily buckle and warp due to the expanding of 30 the air which is trapped between the covering and the support at the places of insecure connection between them. A roof covering so laid will also open up at the joints between the strips providing an entrance for water and moisture to 35 produce leaks. With many loose and insecure connections between the strips and the support, water entering at an open lap or through a defective or damaged strip, may travel a considerable distance under the covering before reaching 40 an outlet in the underlying support. In practice, this may be many feet from the place of entrance, thus requiring a removal of the covering to a considerable extent in making a repair. Warping and buckling of the roof covering not 45 only subjects it to undue strain, pulling it away from its support, but produces an unsightly roof, objected to by owners, engineers and architects, due to its uneven and irregular outer surface. Moreover, a covering of this character is likely 50 to be damaged, when walked upon, due to the 55

bulged portions being unable to support any appreciable weight.

The general purpose and object of my invention is to provide a method by which roofing material of the character referred to may be so laid that the foregoing objections are entirely overcome by reason of the type of the bond provided between the support and the roofing material. 5

In carrying out the objects of my invention, I 10 coat the underside of the roofing sheet preparatory to its application to the support with a hot flowable bituminous material, such as pitch or asphalt, and at substantially the same time apply a coating of said hot flowable bituminous material to the portion of the support to be covered by the sheet. The hot asphalt enters the sheet 15 and breaks down the binder therein, rendering the sheet soft and pliable, whereby the sheet may be properly pressed against the coated support to conform to the contour thereof. The sheet is pressed against the support while the bituminous coatings are still hot, thus obtaining a perfect bond between the sheet and the support. This is possible because the soft, pliable sheet 20 can be pressed throughout its entire area against the coated support to exclude all free air from between the sheet and the support and to adhere the sheet throughout to the support regardless of the irregularity of the latter. Thus, the roof 25 covering when laid cannot buckle, warp or blister, because of the effectiveness of the bond between the sheet and the support and of the absence of entrapped air between them. Also, the covering in fitting the contour of the support will present 30 a smooth and even outer surface. By reason of the bonded connection of the sheet throughout its entire area, a leak through the sheet due to a defect therein will be confined within the defective 35 region and will not spread over the sheet or to 40 adjacent sheets as heretofore.

To avoid undue cooling of the coatings between their application to the sheet and the support, and the pressing of the coated sheet against the coated support, I cut the roofing material as obtained from the manufacturer in sections of a size capable of being readily and easily handled by the workman laying the roof. These sections are individually coated as they are laid, thereby 45 enabling the laying to be carried on while the bonding material is still hot, even in the coldest seasons of the year. In actual practice, the sections are cut to sizes ranging usually 10 feet long 50 by 32 to 36 inches in width, the latter dimension 55

being the usual width of the strips as manufactured.

In laying the sections, they are usually folded or doubled longitudinally on themselves, so that the hot bituminous material may be applied to one half of a section at a time. This lessens the chance of the coating material setting as the sections are laid, due to the rapidity permitted in pressing half of the sections against the coated portion of the support, as compared to the entire area of the section. Only the portion of the support to be covered by half a section is coated at a time, thus keeping the bonding material hot for the proper securing of the section to the support. Applying the bonding material to both the section and the support, produces a double thickness of such material, thus insuring a more effective bond and requiring a longer time to cool which is an important factor in laying the sections.

The accompanying drawing illustrates a roof covering laid in accordance with my invention and also the method of treating and laying the individual sections.

Fig. 1 is a plan view of a portion of the laid covering;

Fig. 2 is an enlarged sectional view, with parts in perspective, taken on line 2—2 of Fig. 1;

Fig. 3 is a plan view of one of the individual sections of roofing material applied to its underlying support prior to being laid by the method of my invention;

Fig. 4 is a view illustrating the first step of my improved method;

Fig. 5 illustrates the second step of the method;

Fig. 6 shows the section of roofing material applied to its underlying support following the steps referred to.

In the drawing, 1, 1 indicates sections of the prepared roofing material heretofore referred to, and 2 indicates the underlying support to which the sections are applied as a covering therefor. The sections 1 are applied to the support 2 in overlapping relation, there being the desired amount of marginal overlap between them. The exposed longitudinal edges of the sections may be straight or they may be serrated, as shown, to increase the effectiveness of the bond of the sections at such edges with the support as set forth in and covered by my Patent No. 1,550,299, granted August 18, 1925.

As heretofore pointed out, the prepared roofing material is supplied in relatively long lengths by the manufacturer and usually in rolled form. In laying this material in accordance with my invention, I cut the long strips into sections, which I have indicated at 1, 1 in the drawing. These sections as previously stated, are approximately 10 feet long by 32 to 36 inches in width, which is the width of the strips as manufactured. This reduces the material to more readily handable form, and the sections so provided are individually treated and laid in the following manner.

The section is first laid at its proper position on the underlying support, as indicated in Fig. 3. In this figure, I have indicated a longitudinal center line 3 which divides the section into longitudinal half portions 4, 5. The half portion 4 contains the front longitudinal edge of the section, this edge being serrated as shown.

The section after being laid on the support, is folded or bent back on itself along its longitudinal center line 3 to position the half portion 4

over the half portion 5, as shown in Fig. 4. This exposes or brings uppermost the underside of the half portion 4, whereupon the workman coats the exposed underside of the section with a coating of hot flowable bituminous material, such as pitch or asphalt, as indicated at 6 in Fig. 4. At the same time, the underlying support 2 in that portion to be covered by the half portion 4, is coated with this hot flowable material, as indicated at 7 in Fig. 4. These coatings may be applied in any desired manner, as by the use of the usual roofing mops 8. In practice, the coatings are applied practically simultaneously, one workman coating the folded over portion of the section and another coating the portion of the support to be covered by the coated section. This is done in order that there shall be no appreciable lapse of time between the application of the coatings and thus both coatings are still hot when the coated portion 4 is swung or dropped down on the coated support 7. In applying the hot coating to the folded over portion of the section, the hot material penetrates the roofing sheet and breaks down the binder of the sheet so that the sheet becomes sufficiently pliable and limp that it may be readily and easily pressed against the coated support throughout its entire area, thereby obtaining a secure and effective bond between the section and the support.

After the coated portion 4 of the section has been secured to the support, the uncoated portion 5 of the section is folded or bent back along the line 3 over the anchored portion 4 as indicated in Fig. 5. The exposed underside of the portion 5 is then coated with the hot bituminous material as at 9 by a mop 8 as shown, and at the same time the portion of the support 2 to be covered by the portion 5 is coated with the same material as indicated at 10 in Fig. 5. These coatings are applied in the same manner as described for the portion 4, and the portion 5 is rendered flexible and limp so that it may be dropped or swung down on its coated support and pressed against the same to complete the bonding of the section to the support. The coated portions of the section are pressed throughout their entire areas firmly against the coatings on the support to exclude all free air from between the section and the support and to intimately connect the section throughout to the support. The section so bonded is indicated in Fig. 6. The coatings 7 and 10 on the support are extended beyond the margins of the section to insure a complete bonding of the section throughout, including its margins, with the support. The coatings are applied to the support to extend under the section where folded along its longitudinal center line while preparing the half portions of the section for laying.

In treating and applying each individual section to the underlying support in the manner shown and described, the several sections are secured throughout to the underlying support, thereby producing a non-buckling, non-blistering and non-warping roof covering. Moreover, as before stated, a bonding union of this character prevents open laps when the sections overlap and also localizes any leaks which may occur in the sections due to defective or damaged material.

In referring to the underlying support, I have reference to not only the support 2, but the overlapped portions of the adjacent sections as shown in Figs. 1 and 2. These portions of the previously laid sections are coated with the hot bonding material when laying the following sections.

In applying the hot flowable bituminous material to the sections and also to the underlying support, I not only secure an effective bond but also double the amount of bonding material employed, thereby retaining the heat longer which is essential when laying the roof covering in cool or cold weather. In rendering the sections limp by the application of the hot bonding material thereto, the sections may be made to conform to the irregular contour of the support on pressing the sections against the same. This is facilitated by having the sections of a size that they may be pressed over their entire surface by the workmen laying them while the coatings are still hot. This insures an effective bond because it includes the high, the low and all intermediate points of the receiving surface of the support, and produces a non-warping and non-buckling roof covering due not only to the intimate connection throughout between the coatings, but to the exclusion of free air between the covering and the support. In practice, the bonding material is used when at a temperature between 450 and 500 degrees Fahrenheit.

The underlying support may be wood, concrete, brick, tile or a composite material of a character employed for roofing purposes. While in Fig. 1, I have shown the roof covering as comprising only one layer, yet it is within the scope of my invention to embody it in as many layers as may be desired. In such case, one layer would cover the other, each layer, however, being laid of individual sections as herein described. After a covering has been laid it may, and usually is, coated with the same bonding material as used for securing the sections to the support.

The details of construction and arrangement of parts shown and described may be variously changed and modified without departing from the spirit and scope of my invention, except as pointed out in the appended claims.

I claim as my invention:

1. The method of laying a prepared roofing sheet on a support, consisting in separately applying two coatings of hot flowable bituminous material, one to the underside of the sheet, and the other to the portion of the support to be covered by the sheet, and then pressing the coated sheet against the coated support while the bituminous coatings on the sheet and the support are still hot to secure an effective bond between the sheet and the support, the coatings being applied to successive half sections of the sheet and to the corresponding portions of the support to be covered thereby to avoid setting of the coating material in the application of the sheet to the support.

2. The method of laying a prepared roofing sheet on a support, consisting in laying the sheet on the support, folding the sheet back on itself to expose the underside of the folded section of the sheet, separately applying two coatings of hot flowable bituminous material, one to the underside of the folded section of the sheet and the other to the portion of the support to be covered thereby, then pressing the coated section of the sheet against the coated support while the bituminous coatings on the sheet and the support are still hot to secure the coated section of the sheet to the coated support, then folding the remaining uncoated section of the sheet back on the portion of the sheet secured to the support, and again separately applying two coatings of

hot flowable bituminous material, one to the underside of the folded section of the sheet, and the other to the portion of the support to be covered thereby, and finally pressing the last coated section against the last coated portion of the support, while the bituminous coatings on the sheet and the support are still hot to secure the entire sheet to the support.

3. The method of laying a prepared roofing sheet on an underlying supporting surface, consisting in separately applying two coatings of hot flowable bonding material, one to the underside of the sheet, and the other to the portion of the supporting surface to be covered by the coated sheet, laying the coated sheet on the coated supporting surface with their coatings in contact, and while the coatings are still hot pressing the coated sheet throughout its entire coated area against the coated supporting surface to cause the coated sheet to follow the contour of the coated support to effectively bond the sheet to the support.

4. The method of laying a prepared roofing sheet on an underlying supporting surface, consisting in substantially simultaneously applying separate coatings of hot flowable bonding material to the entire areas of substantially co-extensive portions of the sheet and the supporting surface, respectively, prior to laying the coated portion of the sheet on the coated portion of the supporting surface, then laying the coated sheet on the coated supporting surface with their coatings in contact, and while the coatings are still hot pressing the coated sheet throughout its entire coated area against the coated supporting surface to cause the coated sheet to follow the contour of the coated support to effectively bond the sheet to the support.

5. The method of laying a prepared roofing sheet containing a bituminous binder on an underlying supporting surface, consisting in separately applying two coatings of hot flowable bituminous material, one to the portion of the supporting surface to be covered by the sheet and the other to the underside of the sheet to prepare the sheet for application to the supporting surface and to break down the binder in the sheet to render the sheet soft and pliable, laying the coated sheet on the coated supporting surface with their coatings in contact, and while the coatings are still hot pressing the soft, pliable coated sheet against the coated supporting surface to cause the coated sheet to follow the contour of the coated support to effectively bond the sheet to the support.

6. The method of laying a readily handleable section of prepared sheet roofing on an underlying supporting surface, consisting in substantially simultaneously applying separate coatings of hot flowable bonding material to successive portions of the sheet and to corresponding portions of the supporting surface, respectively, laying the coated portions of the sheet on the coated portions of the supporting surface to contact the coatings immediately following the application of the coatings to the sheet and the support, and while the coatings on said portions are still hot pressing the coated sheet throughout its entire coated area against the coated supporting surface to cause the coated sheet to follow the contour of the coated support to effectively bond the sheet to the support.

ARTHUR WINDING.
